UNITED STATES PATENT OFFICE.

MICHAEL A. BURKE, OF LIMA, OHIO.

ORGANIZED MECHANISM FOR FLANGING PLATES.

Application filed February 23, 1926. Serial No. 90,200.

My present invention has to do with the flanging of plates, and contemplates the provision of a peculiar and advantageous organized mechanism through the medium of which boiler and tank plates may be expeditiously and easily flanged.

The invention also contemplates the provision of an organized mechanism for the purpose indicated susceptible of application to a standard punch and shear.

Other objects and practical advantages of the invention will be fully understood from the following description and claim when the same are read in connection with the drawings, accompanying and forming part of this specification, in which:

Figure 1 is a view, partly in side elevation and partly in section, illustrative of the organized mechanism constituting the best practical embodiment of my invention of which I am cognizant.

Figure 2 is an end elevation of the same.

Figure 3 is a fragmentary or detail view, partly in elevation and partly in section, showing the clamp wedge of my improvement and the parts adjacent thereto.

Figure 4 is a side elevation of the former comprised in my improvement.

Figure 5 is a top plan view of the said former.

Similar numerals of reference designate corresponding parts in all of the views of the drawings.

The illustrated embodiment of my invention has been successfully used, and has demonstrated its capacity of function in flanging boiler and tank plates to a ninety degree angle. It is susceptible of application to a standard punch and shear, and comprises among other elements a stationary anvil 1, fastened rigidly on the lower portion of a punch. The organized mechanism, also includes a former 2, fastened to the cap or movable head of punch, designated by 3; and the mechanism further includes a clamping means for holding plates in proper position incident to the flanging operation, the said clamping means being made up of an upper block 4, a lower block 5, and a rectilinearly movable clamp wedge 6 between said blocks. As will be readily understood by comparison of Figures 1, 2 and 3, the blocks 4 and 5 and the clamping wedge 6 are held together by dovetail means designated

by 7. The said dovetail connecting means is so disposed that when the wedge 6 is moved rectilinearly, the height of the three parts 4, 5 and 6 is increased or diminished according to the direction in which the wedge 6 is moved. A rack 8 is provided on the wedge 6, and meshed with said rack is a spur gear 9 having by preference the square portion *m*, Figure 1, and adapted to be driven by a standard air motor or any other appropriate driving means. As shown in Figures 1 and 4, the former 2 is provided with a tapered bottom 10, designed to facilitate the passing of a plate to be flanged under said former.

The former 2 is preferably of steel for obvious reasons, and it is arranged as shown in Figure 2 relative to the portions 11 and 12 of the anvil.

Aside from the elements herein explicitly referred to, the associated elements illustrated may be of the construction illustrated or of any other construction and arrangement consonant with the purpose of my invention.

It will be apparent from the foregoing that with my novel organized mechanism, boiler and tank plates and the like may be flanged to a ninety degree angle, and this accurately and expeditiously.

It will further be appreciated that my novel organized mechanism is adapted particularly for flanging long plates which by reason of the construction of the mechanism may be handled with facility for the flanging thereof.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts as disclosed, my invention being defined by my appended claim within the scope of which changes in structures and changes in arrangement may be made without departure from my invention.

Having described my invention, what I claim and desire to secure by Letters Patent, is:

The combination in an organized plate flanging machine, of an anvil, a former, and

clamping means for holding plates in proper position incident to the flanging operation, the said means located in spaced relation from the vertical plane of the former and 5 above the anvil, and being made up of upper and lower blocks, a rectilinearly movable wedge interposed between and dove-tailed

to said blocks and having a rack, and a gear disposed in one block and meshed with said rack for the transmission of rectilinear movement to the wedge. ¹⁰

In testimony whereof I affix my signature.

MICHAEL A. BURKE.
